WRITING INSTRUMENT

Ivan D. Tefft, Janesville, Wis., assignor to The Parker Pen Company, Janesville, Wis., a corporation of Wisconsin

Application August 1, 1946, Serial No. 687,577

3 Claims. (Cl. 120—42.4)

1

This invention relates to ball-point writing instruments and has to do particularly with an ink cartridge for that type of pen, and to a cartridge mounting means.

In writing instruments of the type using a ball-point writing element, it is customary to employ a relatively thick viscous ink and such writing instruments, therefore, do not lend themselves readily to filling by the customer in a manner similar to that employed in filling fountain pens using relatively thin, watery inks. Accordingly, it is desirable in this type of writing instrument to employ an ink-containing cartridge serving as an ink reservoir. It may be desirable in certain cases, in order to insure proper feeding of the thick viscous ink, to provide a cartridge arrangement wherein the ink is placed under pressure continuously tending to urge the ink from the cartridge toward the writing element. Where the ink cartridge is adapted to be removed from the writing instrument so that it can be replaced, when empty, by a full cartridge, this presents the problem of preventing soiling of the hands and clothes of the user by the ink during the operation of replacing the cartridge. The difficulty of preventing leakage of ink from the cartridge during replacement is increased where the ink is under pressure.

An object of the present invention is to provide a ball-point writing instrument having a removable ink cartridge and means for automatically opening the cartridge and placing it in ink feeding relation with a writing element upon insertion of the cartridge in the writing instrument.

Another object of the invention is to provide a ball-point writing instrument having a removable ink cartridge wherein the ink is continuously maintained under pressure tending to urge it from the cartridge, and means for puncturing the cartridge and simultaneously connecting the cartridge with an ink feed leading to the writing element.

A further object of the invention is to provide a readily replaceable ink refill cartridge for a ball-point writing instrument which is simple and inexpensive to manufacture, which can be stocked and dispensed conveniently by retainers without any danger of leakage and which can be inserted in and removed from the writing instrument readily by the user without soiling the hands or clothes of the user.

Still another object of the invention is to provide a point-and-feed unit for a ball-point writing instrument, which unit includes a ball-point

2

writing element and a feed leading thereto and is adapted, when an ink cartridge is inserted in the instrument, to puncture the cartridge, to place the cartridge in ink feeding relation with the writing element and to support the cartridge in the instrument.

Still another object of the invention is the provision of a ball-point writing instrument having a replaceable ink refill cartridge which, when inserted in the writing instrument and moved into its seat therein, is automatically brought into ink feeding relation with an ink feed channel leading to the writing element and is sealed to prevent leakage of ink from between the cartridge and the feed channel defining means.

Other objects and advantages of the invention will appear from the following description taken in connection with the appended drawings wherein:

20 Figure 1 is a longitudinal, sectional view through a writing instrument constructed in accordance with the present invention, the instrument being shown in writing condition;

25 Fig. 2 is a longitudinal, sectional view through the ink cartridge forming a part of the instrument shown in Fig. 1;

30 Fig. 3 is a fragmentary, longitudinal, sectional view through the front end portion of the writing instrument shown in Fig. 1, with the ink cartridge removed;

Fig. 4 is a transverse, sectional view taken along line 4—4 of Fig. 1; and

Fig. 5 is a transverse, sectional view taken along line 5—5 of Fig. 3.

35 Referring now particularly to Fig. 1 of the drawings there is illustrated a ball-point writing instrument constructed in accordance with a preferred embodiment of the invention, which instrument includes a barrel or housing 1 formed of any suitable, rigid material such as metal or a plastic. The barrel 1 preferably is formed with a rear section 2 and a forward section 3, connected together as by screw threads 4. An end cap 5 of any suitable form may be provided for enclosing the writing end of the instrument when the latter is not used in writing, which cap is adapted to be carried on the rear end of the instrument, as shown in Fig. 1, when the instrument is used in writing.

40 The barrel sections 2 and 3 together define a chamber 6 adapted to receive and house an ink cartridge 20. At the forward end of the barrel, a bore or passage 7 of smaller diameter is provided to receive and support a point-and-feed unit 10. The point-and-feed unit 10, which

preferably is formed of a suitable metal, is firmly secured in the forward end of the barrel 1, as by screw threads 11, with its forward end projecting slightly from the forward end of the barrel 1. The forward end 12 of the point-and-feed unit 10 preferably is tapered and is formed with suitable means, such as a socket (not shown), adapted to receive and seat a ball writing element 13. Inasmuch as the details of the socket and the manner of seating the writing element 13 form no part of the present invention, this portion of the point-and-feed unit 10 is not shown in detail, it being understood that any suitable seating arrangement for the ball-point 13 may be employed which properly holds and seats the ball-point 13 for free rotation while suitably permitting feed of ink to the ball-point 13 when the instrument is used in writing. In order to provide for feeding ink to the writing element 13, an ink feed passage or channel 14 of relatively small diameter extends into feeding relation with the ball-point 13 at the forward end of the unit 10. The channel 14 extends longitudinally throughout the length of the unit 10 and is open at the rear end thereof so that the channel may be placed in ink feeding relation with an ink cartridge as hereinafter described in detail.

The point-and-feed unit 10 is formed intermediate its ends, and preferably toward its rearward end, with a portion 19 provided with external threads 15 and comprising a connector element onto which the ink cartridge 20 is adapted to be screwed. The extreme rearward end portion of the point-and-feed unit 10 has a piercing point or element 16 adapted to puncture the end of the ink cartridge and place the interior thereof in ink feeding relation with the ink feed channel 14 which extends from the writing element 13.

The point-and-feed unit 10 is provided adjacent the forward end of the threads 15, with an abutment 17 which preferably takes the form of an annular ring pressed onto or otherwise fixedly secured to the body of the point-and-feed unit 10. Rearwardly of and abutting the ring 17 is a sealing element 18 which preferably is formed as a washer of suitable soft sealing material such as soft rubber, the purpose of which will appear hereinafter.

In accordance with the present invention the removable and replaceable ink cartridge or unit 20 is adapted to be stocked and dispensed by dealers as a unit and can readily be removed from the instrument by the user when the ink is exhausted and replaced by a new and similar unit having a full charge of ink. The unit is fully sealed against leakage of ink therefrom to permit storage in handling and insertion in the writing instrument without soiling the hands or clothes of the user. Moreover, the ink cartridge is adapted to be formed of relatively inexpensive materials so that it can be replaced at a small fraction of the cost of the entire writing instrument.

To the foregoing ends the ink refill cartridge 20 includes a rigid casing or container 21 formed of a material which can be easily and inexpensively formed as by moulding or drawing. Preferably the casing 21 is formed from a suitably rigid plastic, although if desired a metal may be used. The casing 21 preferably is of elongated tubular form and is closed at its rear end and open at its forward end.

The cartridge 20 further includes means for confining the ink and for continuously exerting on the ink a pressure tending to urge the ink from

the reservoir and to cause it to flow through the feed channel to the writing element. In the preferred embodiment of the invention a flexible collapsible sac 22 is disposed within the casing 21 and has its forward open end secured to a nipple 23 preferably formed integrally with an end plug 24 firmly secured in the forward end of the casing 21 as by an adhesive. The end plug 24 is formed with a discharge outlet 26 closed by an initially imperforate, puncturable closure element such as a relatively thin sealing plug 27 securely seated in and closing the discharge outlet 26. The open end of the sac 21 is suitably attached to the nipple 23 to prevent leakage of ink between the sac 21 and the nipple 23. This may be accomplished by adhesively securing the sac to the nipple as by a cement. However, if desired, a clamping ring 25 may be provided in lieu of, or in addition to, the adhesive for clamping the forward end of the sac 22 about the nipple 23.

The cartridge 20 is adapted to be assembled with the point-and-feed unit 13 in such manner that the sealing plug 27 is punctured and the interior of the casing is placed in ink feeding relation with the ink feed channel 14. To this end the end plug 24 is provided with screw threads 28 adapted to engage cooperating threaded means whereby the cartridge 20 may be securely secured in the barrel. In the preferred embodiment, the forward portion of the discharge outlet 26 is threaded as at 28 and adapted to be screwed onto the threads 15 formed on the rearward end of the point-and-feed unit 10.

The casing 21, the end plug 24, the clamping ring 25, and the sealing plug 27 all preferably are inexpensively formed of suitable plastic material or materials. However, if desired any or all of these members may be formed of metal. These members all are formed of a material or materials which provide sufficient rigidity for mechanical strength and, in the case of the end plug 24, a material which may be machined to provide the screw threads 28 which receive the end of the point-and-feed unit 13. The sealing plug 27 is formed of a material which has sufficient strength to retain the ink in the cartridge 20 when the plug is unpunctured, but which can be readily punctured by the piercing point 16 of the point-and-feed unit 10. The sealing plug 27 may be formed with screw threads adapted to fit the threads 28 of the end plug 24 or it may be formed of a material which will adapt itself to the shape of the threads 28 when the sealing plug 27 is inserted in the threaded end of the discharge outlet 26. All portions of both the cartridge and the point-and-feed unit which are contacted by the ink are formed of materials which are not readily deteriorated by inks of the types customarily used in a ball-point writing instrument. Among the materials suitable for forming the sealing plug are "Lucite" (methyl methacrylate resin) and polystyrene; either of these materials also may be used to form the end plug 24 and the casing 21.

The flexible sac 22 preferably is normally collapsed and is adapted to be distended by forcing ink thereinto under pressure, which causes the sac to assume generally the shape of the casing 21. The sac 22 is formed preferably of a resilient material so that the sac will tend always to return to its normal, collapsed condition. Thus, the sac after being filled and distended by the ink is adapted to apply a slight force continuously on the ink tending to urge the ink out of

the sac 22 through the discharge outlet 26. In order to permit the sac 22 to collapse in this manner and conform to the body of the ink therein, the casing 21 is provided with a vent 29 which vents the interior of the casing to the chamber 6 in the barrel; and the barrel 4 in turn is formed with a vent 30 extending from the chamber 6 to the exterior of the barrel, which vents the interior of the barrel to the atmosphere.

After the cartridge 20 has been assembled (except for the sealing plug 27) the sac 22 is distended and the ink is introduced into the sac 22. The sac 22 is held distended by creating a sufficient vacuum around the sac in any suitable manner. Preferably, the cartridge is assembled with a suitable device (not shown) for creating within the space between the sac 22 and the casing 21 a sufficient vacuum to distend the sac 22 substantially to the form which it assumes when filled with ink. An ink suitable for use with a ball-point writing element, as for example a pasty, viscous ink, is then introduced into the sac through the opening 26 in the end plug 24 to completely fill the sac 22 and the portion of the opening 26 up to at least the rearward end of the screw threads 28. With the interior of the casing 21 still maintained under subatmospheric pressure, the sealing plug 27 is inserted in the end plug 24 and firmly seated therein against the body of ink to seal the ink within the sac 22 and the opening 26. The cartridge 20 is then removed from the vacuum-creating device and is ready for use.

The cartridge 20 is assembled with the remainder of the writing instrument, the forward end of the cartridge being inserted through the open rear end of the front section 3, the rear section 2 having been previously removed to permit access to the interior of the front section 3. The end plug 24 is inserted over the rear end of the point-and-feed unit 10 and screwed thereon until the forward end of the cartridge 20 is seated firmly against, and in sealing relation with, the sealing element 18. When cartridge 20 is screwed onto the point-and-feed unit 10 and advances therewith, the piercing point 16 of the latter punctures the sealing plug 27 and places the feed channel 14 in communication with the interior of the sac 22. The ink in the latter thus is forced from the interior of the sac 22 and into the feed channel 14 and thence into feeding relation with the ball point 13. The rear section 2 is then assembled with the front section and the instrument is ready for use. When the ink in the cartridge 20 has become exhausted, the latter may be readily removed and replaced by merely removing the rear section 2 from the front section 3 and unscrewing the cartridge 20 from the point-and-feed unit 10, after which a fully charged cartridge 20 may be assembled with the instrument in the manner above described.

The several parts are so dimensioned that the threads 15 sufficiently engage the threads 28 prior to the time the piercing point 16 punctures the sealing plug 27 so that ink will not leak into the chamber 16. Moreover, when the cartridge is screwed against the seal 18 a further sealing is provided which insures against any leakage into the interior of the barrel. The length of the point-and-feed unit is, of course, such that when the cartridge is fully seated against the sealing ring 18, the rear open end of the feed channel 14 is disposed rearwardly of the sealing plug 27 and fully exposed to permit ink to be forced therein from the interior of the sac 22. Since the sealing

plug 27 closely engages the piercing point 16 during the puncturing of the plug 27, it provides a seal to prevent ink from soiling the threads 15 and 28. Also, the sealing plug 27 serves during removal of the cartridge 20 as a wiper for removing ink from the piercing point 16 so that there is little possibility of ink being left thereon when the cartridge is removed.

From the foregoing it will be seen that the present invention provides a ball-point writing instrument which can be manufactured inexpensively by a relatively small number of simple operations and at a minimum cost for materials. The replaceable cartridge can be formed from relatively inexpensive materials and can be discarded when removed from the barrel after consumption of the ink therein, it is not necessary, however, to discard the point-and-feed unit when the ink cartridge is replaced. The point-and-feed unit, on the other hand, may be removed and replaced readily if, for any reason, this is desired. For example, the point-and-feed unit could be replaced if, after a long period of use, the ball seat should become sufficiently worn to impair the good writing characteristics of the instrument. In connection with the removability of the point-and-feed unit, it should be noted that this unit is threadedly secured in the barrel section sufficiently firm to prevent accidental loosening and displacement of the unit. The point-and-feed unit must be held against the unscrewing tendency which may be developed when the cartridge is screwed onto or off the rearward end of the point-and-feed unit.

The insertion and removal of the ink refill cartridge requires no special skill and can be accomplished by any user. No adjustments are required inasmuch as all the parts except the cartridge are fixably retained in their proper positions. The cartridge seats positively at the end of the screw insertion movement thereof so that the user can determine readily when the cartridge is fully seated and properly positioned for use.

The ink refill cartridge is completely and effectively sealed prior to insertion in the writing instrument and can be stocked and handled without danger of leakage of the ink therefrom. Moreover, the seal is not punctured until after the threads on the cartridge have engaged sufficiently with the threads on the point-and-feed unit so that there is no leakage within the barrel during insertion of the cartridge. Moreover, when the cartridge is fully seated additional sealing means are provided for insuring against leakage of ink into the interior of the barrel.

The screw action employed in assembling the cartridge with the point and feed unit causes the piercing point to cut its way through the sealing plug readily; moreover, the screw action provides a mechanical advantage so that only a very light force is required to screw the cartridge home and puncture the seal. Thus, not only can the assembly operation be performed with a minimum of force but no appreciable strain is placed on the parts by this operation.

I claim:

1. A cartridge for a ball-point writing instrument comprising a rigid casing open at one end, a rigid axially bored end plug secured in and closing the open end of said casing and having a nipple at its inner end, the bore of said plug providing a discharge outlet leading from said casing for receiving therein a threaded end of an ink-feed-and-piercing member and being formed with internal threads of substantial

length longitudinally of the casing for positively but detachably securing said cartridge to the feed member, a resilient flexible sac secured on said nipple for confining ink therein, a vent in said casing on the opposite side of said sac from said nipple, and an imperforate puncturable closure element threaded in said outlet adjacent the inner ends of said threads for sealingly closing said outlet.

2. A self-contained point-feed-and-piercing unit for a ball-point writing instrument of the type including a barrel formed with a cartridge-receiving chamber and an ink-cartridge having a puncturable seal, said unit being adapted to be removably secured in the barrel and to project forwardly therefrom and rearwardly into the chamber, said unit comprising an elongate member having an ink channel extending from end to end throughout said member and open only at said ends, external threads intermediate the ends of said member for positively but removably securing it in the barrel, a generally tubular piercing element at the rear end of and integral with said member for puncturing the seal and entering the cartridge, external threads of substantial length intermediate said first threads and said element for positively but detachably securing the rear end of said unit within the cartridge, an external flange rigid with said member adjacent the forward end of said second threads and having a sealing rear surface of resilient material, and a ball-writing point carried in the forward end of said member.

3. In a writing instrument of the type having a casing formed with a vented chamber and an open forward end, the combination with a self-contained unit including a ball writing point, a tubular member having an ink channel extending from end to end therethrough and opening solely at its ends, and having external threads intermediate its ends for positively but removably securing it in said barrel with its forward end projecting through the open forward end of

the barrel and carrying said ball and its rear end projecting into the chamber and terminating in a fixed tubular piercing element integral with the member, said member also having external threads of substantial length intermediate said first threads and said piercing element and a rigid external flange having a sealing rear surface of resilient material adjacent the forward end of the second said threads, of an ink cartridge including a rigid casing having an internally threaded outlet opening of substantial length longitudinally of the casing for threadedly receiving the second said threads on said member and positively but detachably connecting the cartridge thereto with said piercing element entering in said casing, and an initially imperforate sealing element disposed in said outlet opening adjacent the inner end of the threads therein and puncturable by said piercing element.
